UNITED STATES PATENT OFFICE.

FREDERICK J. X. MILLER, OF OLYMPIA, WASHINGTON.

DESIGN FOR AN EASEL.

SPECIFICATION forming part of Design No. 21,048, dated September 15, 1891.

Application filed August 14, 1891. Serial No. 402,688. Term of patent 14 years.

To all whom it may concern:

Be it known that I, FREDERICK J. X. MILLER, of Olympia, in the county of Thurston and State of Washington, have invented and produced a new and original Design for Easels and other Stands, of which the following is a full, clear, and exact description.

Reference is to be had to the accompanying drawing, forming a part of this specification, in which the figure represents an easel embodying my new design.

The design in its leading features comprises a horseshoe-figure combined with a wish-bone or merry-thought, and in its entirety the design is in the form of a rebus representing, enigmatically, the expression "I wish you good luck."

A indicates the horseshoe, and B the wish-bone figure, the latter appearing at the spaced

ends *a* of the horseshoe and lying partly ²⁰ within the same, its diverging members *b* *b* projecting outward beyond said horseshoe. Between the members *b* of the wish-bone, at the open end of the horseshoe, appears a scroll *c* and a fanciful capital letter "I." Transverse bars *d* appear within the horseshoe beyond the inner end of the wish-bone, and between the said bars appears the fanciful capital letter "U," the latter being indicated by the reference-letter *e*. ²⁵ ³⁰

I claim—

The design for easels or stands herein shown and described.

FREDERICK J. X. MILLER.
